(57) **CLAIM**

The ornamental design for a notebook computer, as shown and described.

DESCRIPTION

FIG. 1 is a front perspective view of a notebook computer showing my new design in an open position;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is an enlarged view of the delineated portion 8 in FIG. 1;
FIG. 9 is an enlarged view of the delineated portion 9 in FIG. 1;
FIG. 10 is an enlarged view of the delineated portion 10 in FIG. 1;
FIG. 11 is an enlarged view of the delineated portion 11 in FIG. 4;
FIG. 12 is an enlarged view of the delineated portion 12 in FIG. 6;
FIG. 13 is an enlarged view of the delineated portion 13 in FIG. 6;
FIG. 14 is a front perspective view of the notebook computer of FIG. 1 shown in an alternative open position;
FIG. 15 is a front elevation view thereof;
FIG. 16 is a rear elevation view thereof;
FIG. 17 is a left side elevation view thereof;
FIG. 18 is a right side elevation view thereof;
FIG. 19 is a top plan view thereof;
FIG. 20 is a bottom plan view thereof;
FIG. 21 is an enlarged view of the delineated portion 21 in FIG. 14;
FIG. 22 is an enlarged view of the delineated portion 22 in FIG. 19;
FIG. 23 is a front perspective view of the notebook computer of FIG. 1 shown in a closed position;

(Continued)

FIG. 24 is a front elevation view thereof;
 FIG. 25 is a rear elevation view thereof;
 FIG. 26 is a left side elevation view thereof;
 FIG. 27 is a right side elevation view thereof;
 FIG. 28 is a top plan view thereof; and,
 FIG. 29 is a bottom plan view thereof.
 The evenly dashed broken lines in the drawings illustrate portions of the notebook computer that form no part of the claimed design.
 The dot-dash broken lines in the drawings delineating portions of the claimed design that are illustrated in enlargements form no part of the claimed design.

1 Claim, 29 Drawing Sheets
